COIN-CONTROL MECHANISM

William J. Kennedy, Hollis, N. Y.

Application March 26, 1937, Serial No. 133,102

17 Claims. (Cl. 235—32)

This invention relates to coin-control mechanism for machines or apparatus designed to be used or operated upon the payment of a fee, usually a coin of a certain value, inserted in a slot 5 in the casing of the machine. Included with this class of slot machines, may be mentioned turnstiles, radio sets, phonographs, games of various kinds, picture exhibiting machines, vending machines and the like.

10 The invention embraces a number of features which are readily adaptable for use in change-making, counting, adding and like machines, handling money in coin form.

In showing the invention applied, I have, as a 15 matter of convenience, embodied it in a form suitable for use in connection with a turnstile but it is to be understood, that this showing is not intended, in any way, as limiting the invention to this particular use and is merely illustrative of one 20 of the many uses for which the invention may be adapted.

In fare collecting turnstiles, as in various other coin-controlled machines, a suitable device is employed to prevent operation until the required 25 coin has been deposited. After the deposit of the coin, the patron or operator actuates a movable member, such, for example, as the rotatable barrier of the turnstile, which, through the inserted coin, is brought into relation to act, either directly or indirectly, upon the aforesaid device, to put the machine in condition for operation.

Attempted actuation of the above mentioned 30 movable member, without first inserting the required coin, ordinarily has no effect upon the machine and in turnstiles, results only in the rotatable barrier checking against further rotation, after it has been advanced a very short distance and has reached the end of its allowable free movement.

35 The turnstile barrier is purposely left free for a short advance movement, to obtain motion necessary to actuate the coin finder of the coin-control mechanism, for the purpose of determining whether or not a coin has been inserted. If 40 a coin is present, it is engaged and advanced by the finder and, in my improved mechanism, the coin, in its advance, imparts movement, through a suitable connection, to the turnstile barrier lock, releasing the same and freeing the machine for 45 operation.

The turnstile having been freed and put into 50 operation, it remains to register the inserted coin by means of a suitable counter and thereafter eject and deposit the coin. This could be accomplished by a comparatively simple mechanism

that would meet all requirements, where the coins used are all alike but, present day practice of transportation companies in establishing different classes of fares, for which they issue coin-shaped disks of different diameters, requires that 5 provision be made in the control mechanism of a fare collecting turnstile, for handling a variety of coins and/or disks, and for making them all effective for releasing the turnstile. It is furthermore required that the different classes of 10 fares be separately registered and totalized and that the inserted coins and/or disks, representing such fares, be rapidly ejected, distributed and deposited in separate receptacles within the machine casing.

To meet these requirements, my improved 15 mechanism, in its present embodiment, provides a common entrance passage for nickels—the regular fare, transfer disks of larger diameter than nickels and token disks—a reduced fare, of larger 20 diameter than transfer disks.

I further provide a coin finder common to the three types of fare disks mentioned, which is adapted to advance them along a common path, in which their travel is checked, according to their 25 diameters, at different points therein. As each coin reaches its limit of travel in the common path, it engages and is held until ejection, by a spring-advanced selector, which action imparts movement to the selector, increasing the tension 30 of its spring and shifting a selector member into engaging relation with a member of its counter which is subsequently actuated to register the fare coin or disk engaged by its selector. As the mechanism is designed to handle three classes of 35 fares, three selectors are employed, each with its counter, so that each class is separately registered. After a fare is registered, ejection of the coin or disk follows and is brought about by withdrawing the support from under the coin or disk, 40 permitting the tensioned selector, by which the coin or disk is held, as above described, to act and speed the discharge. To save the time and labor of sorting the ejected coins and/or disks, they are automatically distributed and deposited, following their discharge, according to the class of fares 45 they represent. This is accomplished by means of separate coin chutes, leading from the several points of discharge to separate receptacles within the casing of the machine.

50 In the accompanying drawings, I have illustrated a form of coin-control mechanism suitable for carrying my invention into effect but do not wish to be understood as intending to limit myself to either the form or details shown, as various 55

changes may be made therein within the scope of the invention as outlined in the appended claims.

In the drawings—

Fig. 1 is a view in elevation, showing mainly the fare-registering assemblage of the coin-control mechanism.

Fig. 2 is a similar view with the registering counters removed to show the coin selectors through which the counters are operated. The selector at the left is shown shifted by an inserted coin (indicated in dotted lines) into position to operate its counter. The coin represented is the nickel cash fare, which is of smaller diameter than the transfer and token disks used.

Fig. 3 is a view in elevation of the mechanism from the side opposite that illustrated in Figs. 1 and 2, with portions of the body plate broken away to show the coin gauge and selector studs in the coin guideway. In this view the mechanism is shown in normal position or inactive.

Fig. 4 is a similar view showing the mechanism in operation after a transfer disk has been inserted, which is of the intermediate diameter used. The coin-finder is shown in position after it has advanced the disk (indicated in dotted lines) to the point where further advance has been stopped by the coin gauge in the guideway and the coin has been moved under and raised the selector stud against the action of its spring. Thus positioned, the coin is held by the tensioned selector stud until it is registered and ejected.

Fig. 5 is a vertical section on the line S⁵—S⁵, of Fig. 3, in which various parts have been omitted for clearness of illustration. The view illustrates, mainly, the coin ejector and distributor and shows the ejector after it has been shifted from an adjusted position, shown in Fig. 6, in which it supports the coin, back to normal position, in which its support for the coin is withdrawn and the distributor is positioned to receive the coin as it is ejected.

Fig. 6 is a similar view showing the position of the ejector and distributor as a coin is being advanced in the coin guideway by the coin-finder.

Fig. 7 is a view in elevation looking at the left side of the mechanism, as viewed in Fig. 3, showing the same in normal or inactive position.

Fig. 8 is a transverse section through the coin guideway, and

Fig. 9 is a top plan view, with the casing removed, showing the barrier-positioning and locking mechanism of a four-arm turnstile and the connections from the same to the coin-control mechanism shown in the other figures of the drawings.

Referring now to the drawings, 1 represents a common entrance passage for coins, and/or metal disks; 2, representing different classes of fares and distinguishable one from the other, usually, by size (diameter), color and lettering.

Forming a continuation of the entrance passage and angularly disposed thereto, there is a coin guideway which the coin enters on leaving the entrance passage and comes to rest on a seat formed by the extended left-hand wall 3 of the entrance passage, as viewed in Figs. 3 and 4, and a cross pin 4 in the guideway. This coin seat, in the present embodiment of the invention, is designed to serve for the three classes of coins or fare disks mentioned above.

At the left of the seated coin, again as viewed in Figs. 3 and 4, and projecting into the coin guideway, there is a lug 5 of an arm 6, which latter will be hereinafter termed the coin-finder.

The coin-finder is pivoted at 7, to have forward and backward movement about its pivot and the coin guideway is given the curved form of an arc, struck from the coin-finder pivot as a center. (See Figs. 3 and 4.)

As best shown in Figs. 5 and 6, the curved guideway for the coin is formed between two sheet metal body plates 8 and 9, which are suitably spaced apart to admit passage of the coins in a restricted path between them and to the right of the cross pin 4, as viewed in Figs. 3 and 4, the guideway is normally open at the bottom, for a purpose to be later explained.

The top of the guideway is closed by a plate 10, secured between the two body plates 8 and 9, and shaped to serve as a coin gauge, to check movement of the coins at different points in the guideway, according to their diameters.

As shown in Figs. 3 and 4, the coin gauge plate 10, is provided with three shoulders 11, 12 and 13, positioned to engage and check movement in the guideway at different points, of coins of the three different diameters, for which the mechanism is designed.

The body plate 8 (see Figs. 3 and 4), is slotted, as indicated at 14, in line with the curved guideway, to permit free forward and backward movement of the lug 5 of the coin-finder therein.

Assuming that a coin of the intermediate diameter is inserted in the entrance passage and comes to rest on the seat at the left-hand end of the coin guideway, as viewed in Figs. 3 and 4. If now, the coin-finder is actuated, its lug, engaging the coin, will advance it toward the right along the guideway, until the coin strikes the intermediate shoulder 12 of the coin gauge, and its further motion along the guideway will be checked and it will remain held at this point between the shoulder of the gauge and the lug of the coin-finder until it is registered and ejected in a manner to be later described.

We have the same operation, as above described, for the larger and the smaller coins or disks but with this difference, the larger coin will travel a shorter distance in the guideway, as will be apparent from the position of the shoulder 11 of the coin gauge and the smaller coin will travel the full length of the guideway.

When coin mechanism such as we have here is in use, it frequently happens that several coins are inserted in the entrance passage by a person paying for himself and others accompanying him and in order to prevent the mechanism from being blocked or jammed, after the coin-finder has advanced the first coin along the guideway, the coin-finder is provided in the rear of the lug 5 with a lip or flange 15, which is given the curvature of the guideway and as the coin-finder moves forward to advance the first coin along the guideway, its lip or flange rides under the entrance passage and provides a closure for the lower end thereof, holding the other coins in the passage until the coin-finder makes its full return movement, when the next coin drops down on the seat and the above described operation is repeated, so that entrance to the guideway will be closed when the mechanism is in operation and will remain closed until each operation is completed.

To reduce friction and ease and steady the motion of the coin-finder, a roller 16, is provided and mounted thereon to ride on the face of the body plate 8, and to provide a definite stop for the coin-finder on its return movement, a rearward extension is employed which terminates

in a bent-up end 17, shaped to engage the edge of the body plates, as best shown in Fig. 7.

The coin-finder is given both forward and backward movement by an actuating arm 18, mounted to turn about the same pivot 1, as the coin-finder and connected to it by a spring 19 (see Figs. 3 and 4). Through this spring the actuating arm 18 gives motion to the coin-finder but is free to move independently of the coin-finder, in opposition to the spring. In other words, the actuating arm 18, must make a full forward stroke in each operation of the mechanism, for reasons which will appear later on and, as the coin-finder is subject to being checked at 15 points short of its full stroke by the larger and intermediate diameter coins or disks, a yielding connection, such as is provided by the spring 19, is required to permit independent movement of these cooperating members.

20 A coin or disk having been inserted and advanced by the coin-finder, as above described, the next step is to register the same before it is ejected.

Provision is made in the present embodiment 25 of the invention for registering each of the three classes of fares the mechanism is designed to handle, on a separate counter, so that the total for each class may be instantly read by a glance at the exposed faces of the counters.

30 It may be mentioned at the outset, that the registering devices for the three classes of fares are identical and are so constructed and arranged, that only one can operate at a time and must complete its operation, before either of the others can be actuated.

In separately registering the three classes of fares, I employ a coin or disk selector for each counter, which is so positioned, as to respond only to one class of fares, the selection depending upon 35 the diameter of the coin or disk.

40 Each selector (see Fig. 2) consists of a centrally pivoted arm 20, turning on a fixed pin 21, projecting from the body plate 9. The arm 20 is provided at the lower end with a stud 22 (see Fig. 5), which projects through a slot 23 in the body plate 9, and on into the coin guideway, at a point adjacent one of the shoulders of the coin gauge 10 therein.

A spring 24, acting on the arm 20, normally 45 maintains the stud 22, at the lower end of the slot 23, and, in this position, the stud will be engaged, moved upward and held by each coin advanced in the guideway by the finder which is of the diameter of the class of fares the counter of the particular selector is intended to register.

55 The upward movement imparted to the selector by the selected coin or disk, serves two important purposes. The selector and its associated counter are, normally, disconnected, as is best shown in Fig. 2, and one purpose served is to bring a member of the selector into cooperative relation with a member of its counter for subsequent operation of the latter, in a manner to be described. The other purpose served is to increase 60 the tension of the selector arm, to make it available for use in speeding the ejection of the coin, as will also be described.

Again referring to Fig. 2, it will be seen that each of the selector arms 20, has pivoted at its 65 upper end, a downwardly extending rod 25, the lower end of which is normally held by a slotted bar 26, slightly to the left and clear of a stud 27, carried by a spring-retracted sector 28. The sector 28 is mounted to turn about a fixed stud shaft 29, projecting from the body plate 9, and is

connected through a link 30 to operate the counter 31.

It will be observed that in the figure of the drawings referred to (Fig. 2), the rod 25 of the selector at the left, has been shifted into position to engage the stud 27 of its cooperating sector 28, while the rods of the other selectors are in normal position or clear of the studs of their sectors. This shifting of the rod at the left, was brought about by a selected coin, indicated 10 in dotted lines, in the guideway, engaging and raising the stud of selector arm at the left, thereby rocking the arm and dropping the rod to the position shown.

With the parts positioned as shown and described, it only remains to move the slotted bar lengthwise, to cause the rod at the left, to engage the sector stud and give the sector the necessary limited rotary movement to pull down on the link and operate the counter, which operation registers the selected coin before it is ejected. 15

The bar 26 has a separate slot formed therein for each of the rods 25, and as the bar is moved lengthwise, it gives simultaneous motion to the several rods and the rod that is shifted downward 25 by a selected coin, gives motion to its sector and through the connection described, operates its counter.

The righthand end of the slotted bar 26 (Fig. 2) moves in a guide 32, and the lefthand end is provided with an opening for a projecting stud 33 of a spring-retracted arm 34, mounted on the opposite side of the body plates. The stud projects through a slot 35 in the body plates and the retractile spring 36 of the arm 34, acting through 35 the stud-connected bar 26, yieldingly maintains the rods 25 in their normal position, that is to say, disconnected from the operating devices of the counters.

Referring to Figs. 3 and 4, the arm 34 is shown 40 mounted on a stud shaft 37, fixed to the body plate 8. The lower free end of the arm 34, is provided with a downwardly projecting tooth 38, which is designed to be engaged by a spring-retracted pawl 39, carried by the actuating arm 18 of the coin-finder. 45

On each forward stroke of the coin-finder actuating arm 18, in which it moves from the position shown in Fig. 3 to the position shown in Fig. 4, the pawl 39, carried thereby, engages but yields 50 and rides under the tooth 38 of the arm 34, without giving motion to the arm. On the return or back stroke of the actuating arm, the pawl, again engaging the tooth of the arm 34, will continue in engagement therewith long enough to impart 55 the necessary motion to the arm 34, to move the above described slotted bar 26, in the direction of its length and so give motion to the several selector rods 25, one of which will be positioned to actuate the sector with which it cooperates and 60 cause registration by the counter of the selected coin, as previously explained.

The inserted coin having been registered by the proper counter for its class of fares, the next 65 step is to eject the coin.

It has been explained that beyond the coin seat at the lower end of the entrance passage, the coin guideway, along which the coin is advanced by the finder, is normally open at the bottom, as shown in Fig. 5.

Below the coin guideway, the body plates 8 and 9 are cut away to provide clearance for an arm 40, which is pivotally mounted on a short cross shaft 41, and is shaped at its upper end 42, to serve as a bottom for the coin guideway. 75

The lower end 43 of the arm 40 and an extension 44 on the actuating arm 18, of the coin-finder, are shaped to cooperate as cams and act, when the mechanism is in normal position or inactive, to maintain the arm 40 with its upper shaped end, clear of the open bottom of the coin guideway, as best shown in Fig. 5, and also shown in elevation in Fig. 3.

Above the cross shaft 41, the arm 40 is provided with a second cam 45, and the actuating arm 18 of the coin-finder, is similarly provided with a second cam 46. These cams 45 and 46, stand in close relation but disengaged when the mechanism is in normal position or inactive.

As will be evident, the purpose of the two sets of cams above described, is to rock the arm 40, and maintain the shaped end thereof in or out of bottoming relation with the coin guideway.

The disengagement of the lower set of cams 43 and 44, and the engagement of the upper set 45 and 46, occurs a moment or so after the coin-finder actuating arm begins to move on its forward stroke and thus shifts the shaped upper end of the arm 40 from the position shown in Fig. 5, to the position shown in Fig. 6, so as to provide a bottom for the coin guideway before an inserted coin is advanced therein by the coin-finder.

Once shifted, as above described, the upper shaped end of the arm 40, is maintained by the cams in bottoming relation with the coin guideway, while the actuating arm of the coin-finder completes its forward stroke and returns almost to its normal position, then the upper cams disengage and the lower cams re-engage and rock the arm 40, withdrawing the upper shaped end clear of the coin guideway and opening the same for the release and ejection of the coin.

As will be apparent, the withdrawal of the bottom of the coin guideway would be sufficient in itself to bring about gravitational discharge of the coin therein but quicker action is desirable and I accordingly utilize the tensioned ejector stud, under which the coin is held in the guideway, to speed up the discharge and eject the coin.

As indiscriminate ejection of coins and/or disks, representing different classes of fares, would necessitate subsequent sorting, I provide for distributing and depositing the coins and/or disks, according to their class, in separate receptacles.

Formed on or attached to the upper part of the arm 40, above the cross shaft and on the side opposite the cams, there are three coin chutes 47, 48 and 49, arranged in line with the selectors above, in the coin guideway. As a coin or disk is ejected by any one of the three selectors, it enters the chute on the arm 40, designed to receive the class of fares represented by the coin and, on leaving the chute of the arm 40, the coin enters a fixed continuation of the same, indicated in dotted lines in Figs. 1 and 2, and is carried by the extension chute and deposited in a suitable receptacle, not shown, usually located within the casing of the machine the coin mechanism is employed to control.

By means of this arrangement, the coins and/or disks are distributed and deposited, according to the class of fares to which they belong, and as the number deposited in each receptacle appears on the counters, it only remains for the collector to separately bag the coins and/or disks, note the number of each and his work is done.

As pointed out in the preliminary statement of invention, the above described coin-control

mechanism may be readily adapted for use on machines and apparatus of various kinds, designed for operation upon the payment of a fee and for a convenient showing of the application of the invention, I have selected a well known form of turnstile such as is used to bar an entrance passage and is normally locked against operation.

Referring to Fig. 9, the essential parts of the turnstile mechanism are shown, with the casing removed, for clearness of illustration.

As there shown, the turning axis of the four-arm rotatable barrier 50 of the turnstile, is indicated at 51. The ratchet wheel 52, fast to and movable with the barrier and the spring-advanced pawl 53, engaging the ratchet, constitute the "back-lock", to prevent reverse movement of the barrier. The disk 54, also fast to and movable with the barrier, is peripherally shaped to provide four equi-spaced stop-shoulders 55, 55 etc., and has mounted upon it four equi-spaced rollers 56, 56 etc. Cooperating with the rollers 56, in pairs, there is a spring-advanced lever 57, pivoted at 58, which acts in the well known manner to position the barrier, with one of its arms across the entrance passage the turnstile controls.

Cooperating in the usual manner with the stop-shoulders 55, 55 etc., there is a spring-advanced locking pawl 59, pivoted at 60. The pawl is normally spaced away, a slight distance, from the stop-shoulder it is positioned to engage and this clearance permits limited free rotary movement of the barrier, which is utilized to operate a coin-finder. If no coin is present, the stop-shoulder 55, engages the end of the locking pawl 59, and checks further forward rotary movement of the barrier. If a coin has been inserted, the coin-finder advances the coin and through connections to be described, imparts the necessary motion to the locking pawl 59, to move it about its pivot, clear of the advancing stop-shoulder, permitting continued rotation of the barrier as required for a complete operation of the turnstile.

The effect of continued rotation of the barrier is to cause the roller 56, engaging the outer free end of the positioning lever 57, to ride under the lever and give it motion towards the right, about its pivot, in opposition to its heavy retractile spring. As the roller 56, passes the high point 61 of the cam face of the positioning lever, which is in the dead center line of the barrier axis, the retractile spring acts, forcing the positioning lever in the reverse direction, towards the left and driving the roller before it, thereby continuing the clockwise rotation of the barrier, under the power of the retractile spring of the positioning lever, until the turnstile completes its operation.

The above described back and forth movement given the positioning lever, is utilized to impart like movement, in reverse direction, to the actuating arm 18, of the coin-control mechanism. This motion is transmitted through a link 62 from the positioning lever to a lever 63, pivoted at 64, and connected by a link 65, with the lower end 65 of the actuating arm 18 of the coin-finder. Through the connection described, rearward movement of the positioning lever to the right, during the first eighth of a revolution of the turnstile barrier, causes the coin-finder to advance the coin in the coin guideway and as the movement of the positioning lever is reversed during the second eighth of a revolution of the turnstile barrier, the coin-finder is caused to return to normal position.

It will be seen that continued rotation of the turnstile barrier, beyond its free initial movement, depends upon the instant withdrawal of the locking pawl 59, from engaging relation with the stop-shoulders 55, of the disk 54. To bring about such release of the barrier, I cause each coin and/or disk, in the first part of its advance by the finder, to impart the necessary movement, through a connection, now to be described, to shift the locking pawl, as required, to release the barrier and permit operation of the turnstile.

Referring to Figs. 3 and 4, a diagonally disposed shaft 66 is shown, mounted in suitable bearings 67, 67, on the body plate 8. Near the upper end, a short arm 68 is made fast to the shaft and its free end projects into the guideway in the path of coins and/or disks advanced therein by the coin-finder. A spring 69 encircling that portion 20 of the shaft between the arm and the upper bearing, acts to yieldingly maintain the arm 68 positioned as above described.

On the lower end of the shaft 66, projecting beyond the lower bearing 67, a curved arm 70 is made fast, with its outer free end normally in 25 engaging relation with a pin 71, projecting upward from the lower end of the barrier-locking pawl 59.

In operation—as an inserted coin or disk is given movement by the coin-finder, in advancing it in the guideway, the coin or disk engages the free end of the arm 68, and as the advance of the coin is continued, it forces the arm outward, thereby giving motion to the diagonally disposed 35 shaft 66, which, in turn, moves the curved arm 70, carried at its lower end, causing the free end of the curved arm to exert sufficient pressure on the pin 71, to swing the barrier-locking pawl 59 about its pivot, clear of the notched disk 54, 40 and release the barrier for operation of the turnstile.

As the coin forces its way by and moves the arm 68 outward, as above described, the coin-finder rides under the free end of the arm and 45 holds it clear of the coin guideway until the coin-finder, on its return or back stroke clears the arm, which is immediately swung into the guideway and thus positioned, by the action of its spring 69, for engagement by the next coin or disk inserted by a person operating the turnstile.

As the free end of the curved arm 70, at the lower end of the diagonally disposed shaft 66, moves forward, in engagement with the pin 71, of the barrier-locking pawl, as above described, 55 it will be noted, that its movement is on a shorter radius than that of the pin of the locking pawl and this results in the pin 71, riding off the free end of the arm 68, and into engagement with the inner curved edge thereof, as indicated by dotted 60 lines in Fig. 9. In thus causing the pin to shift from the end to the inner edge of the arm, the latter is relieved of the strain of further advancing the locking pawl against the increasing tension of its retractile spring and excessive movement 65 of the pawl is avoided.

As the operation and many important advantages of my improved control-mechanism will be apparent from the foregoing, it will not be necessary to further describe the same.

Having described my invention, I claim:

1. In a coin-control mechanism, a single entrance passage for coins of different diameters, a coin-finder adapted to advance inserted coins of different diameters along a common path, 75 means in the path for limiting movement of the

coins along the same according to their diameters, counters for registering the number of coins advanced by the finder, and a coin selector for each counter, each coin selector being operatively disconnected normally from its counter and responsive only to coins of a certain diameter. 5

2. In a coin-controlled mechanism, a single entrance passage for coins of different diameters, a coin-finder adapted to advance inserted coins of different diameters along a common path, means 10 in the path for limiting movement of the coins along the same according to their diameters, counters for registering the number of coins advanced by the finder, a selector for each counter responsive only to coins of a certain diameter, 15 the said selectors adapted to be held under tension by each coin selected, and means for utilizing the tension of the selectors to eject the coins.

3. In a coin-control mechanism, a single entrance passage for coins of different diameters, 20 a coin-finder adapted to advance inserted coins of different diameters along a common path, means in the path for limiting movement of the coins along the same according to their diameters, 25 counters for registering the number of coins advanced by the finder, and a coin selector for each counter adapted to respond only to coins of a certain diameter, said selectors each including a spring-advanced member positioned to be engaged and put under increased tension by the 30 selected coins, and means for utilizing the tensioned selectors to eject the coins.

4. In a coin-control mechanism, a single entrance passage for coins of different diameters, 35 a coin-finder adapted to advance inserted coins of different diameters along a common path, means in the path for limiting movement of the coins along the same according to their diameters, 40 counters for registering the number of coins advanced by the finder, a coin selector for each counter adapted to respond only to coins of a certain diameter, said selectors each including a spring-advanced member positioned to be engaged and put under increased tension by the 45 selected coins, means for utilizing the tensioned 50 selectors to eject the coins, and distributing means for depositing the coins ejected by each selector in a separate receptacle.

5. In a coin-control mechanism, an entrance 55 passage for coins, a coin-finder movable to advance inserted coins to the required point for ejection, a counter for registering the number of coins advanced by the finder, coin ejector means, and a member operatively associated to actuate the finder, counter and ejector by a single forward and back stroke.

6. In a coin-control mechanism, an entrance 60 passage for coins, a coin-finder movable to advance inserted coins to the point required for discharge, a member movable from normal position into position to support the coin in its advance by the finder, and means for shifting the member back to normal position to withdraw its support and permit gravitational discharge 65 of the coin.

7. In a coin-control mechanism, an entrance 70 passage for coins, a tensioned coin-ejector at a point distant from the passage, a coin-finder movable to advance inserted coins into engaging relation with the tensioned ejector, a member 75 supporting the coin in its advance by the finder, and means for shifting the member to withdraw its support and permit the ejector to discharge the coin.

8. In a coin-control mechanism, an entrance 75

passage for coins, a coin-finder movable to advance inserted coins to the point required for discharge, an actuating arm for the coin finder, a member pivotally mounted for movement at 5 right angles to the direction of movement of the finder, cams on the member and on the actuating arm of the finder cooperating to move the member from normal position to support the coin as the latter is advanced by the finder and 10 to subsequently shift the member back to normal position to withdraw its support and permit gravitational discharge of the coin.

9. In a coin-control mechanism, an entrance passage for coins of different diameters, a coin-finder movable to advance inserted coins to different points for discharge according to their 15 diameters, and a combined coin-supporting member and distributor, the said member serving as a support for the coins in their advance 20 by the finder, and means for shifting the member to withdraw its support and move the distributor into position to receive and distribute the released coins according to their diameters.

10. In a coin-control mechanism, an entrance 25 passage for coins, a coin-finder adapted to advance inserted coins to the point required for ejection, an actuating arm for the coin-finder, a counter for registering the number of coins advanced by the finder, a spring retracted member 30 operatively associated with the counter and positioned to be tensioned by each advanced coin and coin-releasing means utilizing the tensioned member to speed ejection of the coin, the said coin-releasing means being actuated by the actuating arm of the coin-finder.

11. In a coin-control mechanism, an entrance 35 passage for coins, a coin-finder adapted to advance inserted coins to the point required for ejection, an actuating arm for the coin-finder, a counter for registering the number of coins 40 advanced by the finder, a spring retracted member operatively associated with the counter and positioned to be tensioned by each advanced coin and coin-discharging means utilizing the tensioned member to speed ejection of the coins, the actuating arm of the coin-finder cooperating to first position the coin-discharging means to support the coins advanced by the coin-finder and subsequently re-position said means to remove 45 the support and permit the coins to be ejected.

12. In a coin-control mechanism, an entrance 50 passage for coins, a coin-finder adapted to advance inserted coins to the point required for ejection, a counter for registering the number of 55 coins advanced by the finder, a spring retracted member operatively associated with the counter and positioned to be tensioned by each advanced coin, a coin support, and means spring-connected to but movable independently of the coin-finder 60 for shifting said support clear of the coin on the back stroke of the coin-finder to permit said tensioned member to eject the coin.

13. In a coin-control mechanism, a single entrance 65 passage for coins of different diameters, a coin-finder adapted to advance inserted coins of different diameters along a common path, counters for registering the number of coins advanced by the finder, a coin-selector for each counter 70 normally disconnected from its counter, each of the said selectors being constructed and positioned in the aforesaid common path to be given limited movement by the coin it selects, means utilizing the movement imparted to a selector by

a coin to operatively connect that selector with its counter, and requisite actuating means for giving motion to the selector to operate the counter.

14. In a coin-control mechanism, a single entrance 5 passage for coins of different diameters, a coin-finder adapted to advance inserted coins of different diameters along a common path, counters for registering the number of coins advanced by the finder, a coin-selector for each counter 10 normally disconnected from its counter, each of the said selectors being constructed and positioned in the aforesaid common path to be given limited movement and held under tension by the coin selected, means utilizing the movement imparted to any one of the several selectors by a 15 coin to position a member of that selector for engagement with a member of its counter, and means for actuating the selector member to operate the counter and for subsequently releasing 20 and discharging the coin.

15. In a coin-control mechanism, a single entrance 25 passage for coins of different diameters, a coin-finder adapted to advance inserted coins of different diameters along a common path, counters for registering the number of coins advanced by the finder, a coin-selector for each counter 30 normally disconnected from its counter, each of the said selectors being constructed and positioned in the aforesaid common path to be given limited movement and held under tension by the coin selected, means utilizing the movement imparted to any one of the several selectors by a 35 coin to position a member of that selector for engagement with a member of its counter, means common to the aforesaid members of the several 40 selectors for actuating the same and means for subsequently releasing and discharging the coin.

16. In a coin-control mechanism, a single entrance 45 passage for coins of different diameters, a coin-finder adapted to advance inserted coins of different diameters along a common path, an actuating arm for the coin-finder, counters for registering the number of coins advanced by the 50 finder, a coin selector for each counter, each of the selectors being constructed and positioned to be given limited movement by the coin selected, means utilizing the movement imparted to any one of the selectors by a coin to position a member of that selector for engagement with a member of its counter, and means for transmitting 55 motion from the finder-actuating arm to the aforesaid selector members to operate the proper counter for the coin selected.

17. In a coin-control mechanism, a single entrance 60 passage for coins of different diameters, a coin-finder adapted to advance inserted coins of different diameters along a common path, an actuating arm for the coin-finder, the said arm being mounted to have forward and back movement about a center, counters for registering the 65 number of coins advanced by the finder, a coin-selector for each counter normally disconnected from its counter, means utilizing each coin advanced by the finder to operatively connect the 70 selector of a coin with the counter for that selector, and means for simultaneously transmitting motion from the finder-actuating arm on its back stroke to the aforesaid members of the several 75 selectors to operate the proper counter of the coin selected.

WILLIAM J. KENNEDY.
